UNITED STATES PATENT OFFICE.

EUGENE W. CALDWELL, OF NEW YORK, N. Y.

X-RAY TUBE.

1,029,850

Specification of Letters Patent. Patented June 18, 1912.

Application filed March 13, 1909. Serial No. 483,182.

To all whom it may concern:

Be it known that I, EUGENE W. CALDWELL, a citizen of the United States, and resident of the city, county, and State of New York, have made a certain new and useful Invention Relating to X-Ray Tubes, of which the following is a specification, taken in connection with the accompanying drawings, forming part of the same.

This invention relates to X-ray tubes and relates especially to tubes adapted for use in radiographic work and in which the target is formed with a recess which the cathode stream enters to impinge on the focal surface at the bottom of the recess and thereby generate X-rays which may be transmitted through the recess, the inclosing portions of the target acting as a shield to intercept all the rays, except those constituting the useful cone of X-rays, which may pass through a window in the cathode itself or through a laterally arranged window in the target.

In the accompanying drawing showing illustrative embodiments of this invention in a somewhat diagrammatic way in which the same reference numeral refers to similar parts in the several figures, Figure 1 is a longitudinal section of an X-ray tube. Fig. 2 is a similar sectional view of a modified form of tube.

As indicated in the illustrative embodiment of this invention shown in Fig. 1 the X-ray tube may comprise the cylindrical body 1 of relatively small dimensions having the reduced end 2 in which the target support 12 may be mounted in any desired way and connected with the target terminal 13 on the outside of the tube. This reduced cylindrical form of tube body minimizes breakage and also allows a suitable jacket 18 of lead glass or other material impervious to the X-rays and other undesirable radiation to be readily supported around the tube body where the X-rays are developed. The target which as indicated is quite closely embraced by the body 1 of the tube may comprise the heavy metallic portion 11 secured to the support 12 if desired and provided with the focal surface 8 of platinum or other suitable material to receive the cathode stream. The target may as indicated be formed with a suitable recess 14, the shield extensions 9 of

the target being formed of heavy metal, such as copper, which is substantially impervious to the X-rays and other radiation emitted from the focal surface. If desired, suitable interceptors or ridges 10 may be formed on the shield extensions of the target so as to intercept undesirable radiation and minimize the secondary radiation issuing from the target recess. If desired, a suitable glass envelop 15 may be provided within the tube inclosing the target to the desired extent so as to modify to the desired extent the electrical discharge through the tube.

The cathode may be supported in the exhausted tube chamber by any desired means as by the stem 4 connected to the cathode adjacent its outer edge and mounted in a suitable arm 3 of the tube and connected with the cathode terminal 5 on the outside of this arm. The cathode may also in some cases if desired be further supported in proper position with relation to the target by suitable retainers 7 fused into or otherwise supported by the tube. As indicated the cathode may be formed with a centrally located window 16 transparent to the X-rays which may be either in the form of an aperture through the cathode or a comparatively thin plate of aluminum so as to allow the useful cone of X-rays to be transmitted readily without interrupting the concave working face of the cathode. When the tube is operated the cathode stream enters the target recess and is focused on the focal surface 8 developing X-rays which after transmission through the window 16 of the cathode form the useful pencil of rays 17. While of course being useful for treatment purposes this ray cone is especially desirable for radiographic work because it produces sharp shadows by reason of the elimination of the undesirable secondary and irregular radiation.

In the illustrative embodiment of the invention shown in Fig. 2, the body 1 of the glass tube is indicated as having a substantially cylindrical form and closely inclosing the cathode and target. The target is mounted on a suitable tubular or other support 12 held within the reduced portion 2 of the exhausted tube and electrically connected with the target terminal 13. The target may comprise the massive metallic portion 11

provided with a suitable recess 14 within which the focal surface 8 of platinum or other resistant material is mounted at a suitable inclination. The radiation from the focal surface may thus pass through a lateral aperture 25 in the side of the target which may if desired be covered by a window 26 formed of a thin sheet of aluminum or other suitable material which is substantially transparent to X-rays, but impervious to other undesirable radiation which is thereby prevented from impinging on the glass body of the tube and generating heat and other undesirable radiation thereon. The target may as indicated be formed with the shield extensions 9 and with the interceptors or ridges 10 at the edges of the receiving recess so as to minimize the emission of undesirable radiation therethrough. The cathode 15 may be mounted on the stem 22 supported by the glass member 23 secured to the tube and electrically connected with the cathode terminal 24. If desired a suitable jacket 18 of lead glass or other material substantially impervious to X-rays may be mounted around the body of the tube so as to still further cut off undesirable radiation without interrupting the useful cone of rays 27 issuing through the window 26. If desired the tubes may be provided with the usual 30 vacuum regulators indicated as comprising the arm 28 having the regulator terminal 29 fused therein and provided with suitable regulating material 30.

Having described this invention in connection with a number of illustrative embodiments thereof, to the details of which disclosure the invention is not of course to be limited, what is claimed as new and what is desired to be secured by Letters Patent is set forth in the appended claims.

1. The X-ray tube having a massive target of material substantially impervious to X-rays and provided with a deep recess to receive the cathode stream entering said target, there being a resistant lining in said recess upon which said cathode stream strikes, a cathode to coöperate with said target, said tube having a substantially cylindrical glass body closely surrounding said target and said cathode, interceptors formed on said target to minimize the discharge of undesirable radiation through the opening in said target through which the cathode stream enters, a window of material substantially transparent to X-rays mounted on said target to cover a lateral opening therein through which the X-ray cone passes before striking the body of said tube and 60 a jacket of material substantially impervious to X-rays closely surrounding the cylindrical portion of said tube body.

2. The X-ray tube having a massive tar-

get of material substantially impervious to X-rays and provided with a deep recess to receive the cathode stream entering said target, a cathode mounted in said tube to coöperate with said target, said tube being formed with a substantially cylindrical glass body closely surrounding said target and 65 cathode, interceptors formed on said target to minimize the discharge of undesirable radiation therefrom and a window substantially transparent to X-rays mounted on said target over a lateral discharge opening 70 therein through which the X-rays pass before striking the body of said tube.

3. The X-ray tube having a target substantially impervious to X-rays and provided with a deep recess to receive the cathode stream entering said target, a cathode mounted in said tube to coöperate with said target, said tube having a small glass body closely inclosing said target and said cathode and a window of material substantially 85 transparent to X-rays and intercepting undesirable radiation mounted within said tube and through which the X-rays pass before striking the body of said tube.

4. The X-ray tube having a target provided with a resistant lining to receive the cathode stream, a cathode mounted within said tube to coöperate with said target, said tube having a substantially cylindrical glass body in close lateral engagement with said target and said cathode, means mounted within said tube to intercept the undesirable radiation from said target and a window of material substantially transparent to X-rays and intercepting undesirable radiation 100 mounted within said tube and through which the useful X-rays pass before striking the body of said tube.

5. The X-ray tube having a target provided with a resistant lining upon which the cathode stream strikes, a cathode mounted within said tube to coöperate with said target, said tube having a glass body of small lateral dimensions to closely engage said target and said cathode, means on said 110 target to intercept undesirable radiation therefrom and a window mounted within said tube and substantially transparent to X-rays and impervious to undesirable radiation through which the useful X-rays pass 115 before striking the body of said tube.

6. The X-ray tube having a massive target of material substantially impervious to X-rays and provided with a deep recess to receive the cathode stream entering said target, a cathode mounted within said tube to coöperate with said target, intercepting means on said target to intercept undesirable radiation therefrom and a window of material substantially transparent to X-rays and 125 impervious to undesirable radiation mount-

ed within said tube in the path of the useful X-rays before they strike the body of said tube.

7. The X-ray tube having a target, a cathode mounted within said tube to operate within said target, intercepting means mounted within said tube to intercept undesirable radiation from said target and a window of material substantially

transparent to X-rays and impervious to undesirable radiation mounted within said tube in the path of the useful X-rays before 10 they strike the body of said tube.
